[57] ABSTRACT

Compounds represented by the formula

wherein R¹ is a member of the group consisting of CH₃, C₂H₅ and C₃H₇, and R² in position 2, 4, 5 or 6 on the benzene nucleus is a member of the group consisting of F, Cl, Br, CH₃, C₂H₅ and C₃H₇, pharmaceutical compositions containing these compounds, and the use thereof for therapeutic purposes.

2 Claims, No Drawings

**1-(3-HYDROXY-4-ALKYL-PHENYL)-
ALKYLAMINES(-2) AND THE SALTS THEREOF**

This application is a division of Ser. No. 811,662 filed 03/28/69 and now U.S. Pat. No. 3,655,737; which is a continuation of application Ser. No. 171,017, filed Aug. 11, 1971 and now abandoned.

The present invention relates to substituted hydroxylphenyl-alkylamines having valuable pharmacological properties and pharmaceutically acceptable salts thereof. The compounds of the invention are of particular value as hypertensive agents and as agents for treatment of mental illness, especially as antidepressant agents. The invention also relates to methods for the preparation of such compounds, compositions containing them and the use of such compounds for therapeutic purposes. In particular the invention relates to compounds of the formula

I

wherein R¹ is a member of the group consisting of CH₃, C₂H₅ and C₃H₇, and R² in position 2, 4, 5 or 6 on the benzene nucleus, is a member of the group consisting of F, Cl, Br, CH₃, C₂H₅ and C₃H₇.

Prior art compounds are 3-hydroxy-4-methyl-norephedrine;

(II)

and α -methyl-m-tyramine:

(III)

The compounds of this invention have been shown to possess antihypertensive and antidepressant properties without giving rise to undesired sympathomimetic side effects. Surprisingly it has been found that the compounds of the invention are able to penetrate into the brain, where they are taken up by the noradrenergic neurons and act there as "false transmitters". This valuable and unexpected property contributes to the antihypertensive and antidepressant activity of the compounds.

The prior art compound II has no antihypertensive and antidepressant effects, since it does not penetrate into the brain and displace noradrenaline there.

The prior art compound III does penetrate the blood brain barrier, but shows a high sympathomimetic activity which leads to an increase in blood pressure. The increase in blood pressure caused by this side effect overshadows the antihypertensive effect which might be expected from the ability of the compound to act as a false transmitter in the noradrenergic neurons of the brain. Furthermore, the compound III is more toxic than the compounds disclosed in this invention.

An additional advantage of the compounds of this invention over the mentioned prior art compounds is that the substances disclosed herein are able to liberate 5-hydroxytryptamine in the brain. This property contributes mainly to the antidepressant activity of the compounds. None of the mentioned prior art compounds shows this effect.

The compounds of the invention may be prepared by known methods such as

A. replacing Z¹ with H in a compound of the formula

II

40

45

50

55

wherein R¹ and R² have the meanings specified above and wherein Z¹ is a member of the group consisting of alkyl and acyl protecting groups, by means of a strong acid such as HBr to the formation of a compound of the formula I;

B. replacing Z² with H by catalytical hydrogenation of a compound of the formula

III

60

65

wherein R^1 has the meaning specified above; R^3 is a member of the group consisting of $-CH_3$, $-C_2H_5$ and $-C_3H_7$; and wherein Z^2 is a member of the group consisting of aralkyl protecting groups, such as benzyl; to the formation of a compound of the formula I;

5

C. reducing a compound of the formula

VI

10

IV 15

wherein R^1 and R^2 have the meanings specified above, in the presence of $HCOOH$ according to Leuckart to the formation of a compound of the formula I;

25

D. reducing a compound of the formula

V 35

wherein R^1 has the meaning specified above and wherein R^3 is a member of the group consisting of $-CH_3$, $-C_2H_5$ and $-C_3H_7$, to the formation of a compound of the formula I;

40

E. reducing a compound of the formula

45

Starting materials for the processes described above may be prepared in any desired way. Some of the possible ways for preparation of starting materials used in the methods A, B, C and E above are outlined in the following reaction schemes, which also serve as further illustrations of the various methods of preparation as described above. The substituents R^1 , R^2 , R^3 used in the reaction formulas have the meanings given above, Z^3 is hydrogen or the radical Z^1 , and Z^4 is hydrogen or the radical Z^2 .

Starting materials for the reaction way D may be prepared by methods well known per se.

Method A:

Method B:

Method C:

Method E:

The compounds of the invention exist in the form of optically active isomers, which may be isolated in any principally known way for resolution of an amine, and it is understood that such a manner will be included within the scope of this invention.

The racemate obtained at the above reactions can be resolved into the enantiomers by converting the free base into a salt or an amide of an optically active acid such as tartaric acid or any other optically active acid capable of forming crystalline salts with the amine, and

60 regeneration of the amine after the usual separation of the diastereomeric mixture thus obtained.

It will also be understood that the compounds of the present invention may be used either as a purified isomer which is biologically active or in the form of the mixed isomeric product obtained as a natural consequence of the reaction sequences described above, or any other reaction sequence for the preparation of the compounds which results in a mixed isomeric product containing the biologically active isomer or isomers.

The new compounds according to the invention may be administered in the form of salts with physiologically acceptable acids. Suitable acids which may be used are, for example, hydrochloric, hydrobromic, sulphuric, fumaric, citric, tartaric, maleic or succinic acid.

The invention further provides pharmaceutical compositions comprising as active ingredient at least one of the compounds according to the invention in association with a pharmaceutical carrier. Such compositions may be designed for oral, rectal or parenteral administration.

To produce pharmaceutical preparations in the form of dosage unit for oral application containing a compound of the invention in the form of the free base, or a pharmaceutically acceptable salt thereof, the active ingredient may be mixed with a solid, pulverized carrier, for example lactose, saccharose, sorbitol, mannitol, a starch such as potato starch, corn starch, maize starch or amylopectin, a cellulose derivative or gelatin, and also may include lubricants such as magnesium or calcium stearate or a Carbowax or other polyethylene glycol waxes and compressed to form tablets or centres for dragees. If dragees are required, the centres may be coated, for example with concentrated sugar solutions which may contain gum arabic, talc and/or titanium dioxide, or alternatively with a lacquer dissolved in easily volatile organic solvents or mixtures of organic solvents. Dyestuffs can be added to these coatings. For the preparation of soft gelatin capsules (pearl-shaped closed capsules) consisting of gelatin and, for example, glycerol, or similar closed capsules, the active substance may be admixed with a Carbowax. Hard gelatin capsules may contain granulates of the active substance with solid, pulverized carriers such as lactose, saccharose, sorbitol, mannitol, starches (for example potato starch, corn starch or amylopectin), cellulose derivatives or gelatin, and may also include magnesium stearate or stearic acid. Dosage units for rectal application may be in the form of suppositories comprising the active substance in admixture with a neutral fatty base, or gelatin rectal capsules comprising the active substance in admixture with a Carbowax or other polyethylene glycol waxes. Each dosage unit preferably contains 1 to 200 mg of active ingredient.

Liquid preparations for oral application may be in the form of syrups, suspensions or emulsions, for example containing from about 0.1 to 20% by weight of active substance and also, if desired, such adjuvants as stabilizing agents, suspending agents, dispersing agents, flavouring agents and/or sweetening agents.

Liquid preparations for rectal administration may be in the form of aqueous solutions containing from about 0.1 to 2% by weight of active substance and also, if desired, stabilizing agents and/or buffer substances.

For parenteral application by injection the carrier may be a sterile, parenterally acceptable liquid e.g. pyrogen-free water or an aqueous solution of polyvinylpyrrolidone, or a parenterally acceptable oil, e.g. arachis oil, and optionally stabilizing agents and/or buffer substances. Dosage units of the solution may advantageously be enclosed in ampoules.

When given by oral or rectal administration, the compounds of the invention such as 1-(m-hydroxy-p-methylphenyl)-butylamine (-2) and 1-(m-hydroxy)-p-methylphenyl-propylamine (-2), may be given in widely varying dosages from, for example, 20 mg/day to 1 g/day, but dosages of 50-500 mg/day will ordinary

be given, amounts between 100 and 300 mg/day being usually preferred. When given by i.v. administration, dosages of about 5-100 mg/day, preferably about 10-50 mg/day may be used.

The invention is further illustrated by the following Examples.

EXAMPLE 1

Preparation of Starting Material

a. Preparation of 1-(m-methoxy-p-methyl-phenyl)-2-nitro-1-propene

28.9 g of m-methoxy-p-methylbenzaldehyde was dissolved in 75 ml of toluene and refluxed with 46.8 g of nitroethane, 1.5 ml of acetic acid, 1.5 ml of n-butylamine and 0.15 g of p-toluenesulfonic acid until the theoretical amount of water was split off. The solution was evaporated and the residue was purified by recrystallisation from ethanol-water.

The compounds specified in the following Table 1 were obtained in an analogous manner. R¹ and R² have the significance given above, and Z is used to designate the protecting group used in the synthesis.

Table 1

R ¹	R ²	Z	M.p. °C
CH ₃	4-CH ₃	CH ₃	51
CH ₃	5-CH ₃	CH ₃	
CH ₃	6-CH ₃	CH ₃	48
CH ₃	4-C ₂ H ₅	COCH ₃	47
C ₂ H ₅	4-CH ₃	CH ₃	76
C ₃ H ₇	4-CH ₃	CH ₃	65
CH ₃	4-Cl	CH ₃	80
C ₂ H ₅	4-Cl	CH ₃	88

b. Preparation of m-methoxy-p-methyl-phenylacetone

To a solution of 0.8 mole of 1-(m-methoxy-p-methyl-phenyl)-2-nitro-1-propene in 300 ml of toluene and 875 ml of water was added 326 g of iron powder and 3.3 g of ferric chloride hexahydrate. The mixture was

stirred and heated to 80°C. 292 ml of conc. hydrochloric acid was added at such a rate that reflux was maintained. After addition of the hydrochloric acid, the mixture was stirred and refluxed for one half hour, and thereafter steam-distilled. The distillate was extracted

with ether, and the organic layer washed twice with a 3 per cent sodium bisulphite solution, then water, dried over anhydrous magnesium sulphate and evaporated. The remainder was pure enough for the next step.

c. Preparation of 1-(m-methoxy-p-methyl-phenyl)-propylamine (-2)

0.044 mole of the substituted 2-phenylpropanone, 13.5 g of freshly distilled formamide and 2.5 g of 100% formic acid was refluxed with stirring during 5 hours. After cooling 50 ml of water and 50 ml of hydrochloric acid was added and the mixture refluxed for 5 hours. After alkalisation with 30% NaOH the product was taken up in ether. The organic layer was dried and evaporated.

d. Preparation of 1-(m-methoxy-p-methylphenyl)-propylamine-2

67.1 g of 1-(m-methoxy-p-methylphenyl)-2-nitro-1-propene in 200 ml of dry ether was added to a stirred mixture of 32 g of LiAlH in 1000 ml of dry ether at such a rate that the solvent refluxed gently without external heating. The mixture was stirred and heated for 2 hours. 20 ml of ethyl-acetate was then added carefully with vigorous stirring, followed by 40 ml of water. The mixture was filtered and the ethereal solu-

tion was shaken with 2-N hydrochloric acid. The amine was obtained upon alkalisation of the acidic solution and ether extraction. The product could be used without further purification in the subsequent step. The compounds specified in Table 2 were prepared by the same method. R¹ and R² have the significance given above, and Z is used to designate the protecting group used.

Table 2

R ¹	R ²	Z	Yield %
CH ₃	4—CH ₃	CH ₃	68
CH ₃	5—CH ₃	CH ₃	40
CH ₃	6—CH ₃	CH ₃	75
C ₂ H ₅	4—CH ₃	CH ₃	87
C ₃ H ₇	4—CH ₃	CH ₃	80
CH ₃	4—Cl	CH ₃	55

EXAMPLE 2

Preparation of

1-(m-hydroxy-p-methylphenyl)-propylamine-2

a. 39.3 g of 1-(m-methoxy-p-methylphenyl)-propylamine-(2) in 300 ml of concentrated hydrobromic acid (d=1.49) was refluxed for 3 hours. The solution was then evaporated to dryness and dissolved in water. The water solution was made slightly alkaline with ammonia and the precipitate recrystallized from di-isopropylether.

In an analogous way the following substances were prepared. R¹ and R² have the significance given above.

Table 3

R ¹	R ²	M.p. °C
CH ₃	4—CH ₃	134
CH ₃	5—CH ₃	100
CH ₃	6—CH ₃	131
C ₂ H ₅	4—CH ₃	107
C ₃ H ₇	4—CH ₃	117
CH ₃	4—Cl	137

b. 1.81 g of m-hydroxy-p-methyl-norephedrine was dissolved in 20 ml of 1N hydrochloric acid and hydrogenated with Pd/C as catalyst at 50°. After 5 hours 250 ml of H₂ had been taken up and the desoxybase was isolated by alkalisation of the filtered solution. After recrystallization from di-isopropylether the melting point was found to be 134°C. The substance was identical with the one obtained in example 2a.

EXAMPLE 3

Preparation of

1-(m-hydroxy-p-ethyl-phenyl)-propylamine(-2)

1-(m-hydroxy-p-ethyl-phenyl)-propylamine (-2) was prepared by reduction of 1-(m-hydroxy-p-ethyl-phenyl)-2-nitro-1-propene by means of LiAlH₄ by the same method as in Example 1d. M.p: 109°C.

The following Examples illustrate how the compounds of the instant invention can be incorporated in pharmaceutical compositions.

EXAMPLE 4

Tablets

Each tablet contains:
Active substance 50.0 mg
Maize starch 25.0 mg

-continued

Lactose	160.0 mg
Gelatin	1.5 mg
Talc	12.0 mg
Magnesium stearate	1.5 mg
	250.0 mg

EXAMPLE 5

Suppositories

Each suppository contains:	
Active substance	50.0 mg
Ascorbyl palmitate	1.0 mg
Suppository base (Imhausen H)	ad 2000.0 mg

EXAMPLE 6

Syrup

Active substance	0.500	g
Liquid glucose	30.0	g
Sucrose	50.0	g
Ascorbic acid	0.1	g
Sodium pyrosulfite	0.01	g
Disodium edetate	0.01	g
Orange essence	0.025	g
Certified colour	0.015	g
Purified water	ad 100.0	g

EXAMPLE 7

Injection Solution

Active substance	0.100 mg
Sodium pyrosulfite	0.500 mg
Disodium edetate	0.100 mg
Sodium chloride	8.500 mg
Sterile water for injection	ad 1.000 mg

EXAMPLE 8

Solution for Rectal Administration (Rectal Vials)

Active substance	20.0 mg
Sodium pyrosulfite	1.5 mg
Disodium edetate	0.3 mg
Sterile water	ad 3.0 ml

EXAMPLE 9

Drops

Active substance	2.00 g
Ascorbic acid	1.00 g
Sodium pyrosulfite	0.10 g
Disodium edetate	0.10 g
Liquid glucose	50.00 g
Absolute alcohol	10.00 g
Purified water	ad 100.0 ml

EXAMPLE 10

Tablets

Active substance (50 g), lactose (100 g), calcium citrate (50 g), and starch (50 g) are mixed together and granulated using a 10% aqueous gelatin solution. The granules are passed through a 20-mesh sieve, mixed with magnesium stearate (1.5 g) and talc (5 g), and then tabletted using a 9 mm punch.

PHARMACOLOGICAL TESTS

I. Effect as Releasers and Displacers of Noradrenaline in the Mouse Brain

The substances were given intraperitoneally to mice (male, NMRI, b.w. of 18-22 g) in a dosage of 30 mg/kg. 6 animals per group were used. The noradrenaline in the brains was determined fluorimetrically according to Bertler, Carlsson and Rosengren, Acta physiol. scand. 44, 273 (1958) 1, 2, 4 and 8 hours after the administration. The values are given in percents of normal values (450 ± 9 ng/g).

Table 4

R ¹	R ²	Amount of noradrenaline in the brain. Percent of normal values after				Sympathomimetic effect (piloerection salivation, exoftal- mos)
		1	2	4	8 hrs	
CH ₃	4-CH ₃	60.6	48.6	37.5	48.1	+
CH ₃	4-C ₂ H ₅	75.8	68.3	60.5	68.5	-
C ₃ H ₇	4-CH ₃	91.0	85.4	80.0	92.5	-
C ₂ H ₅	4-CH ₃	90.1	87.4	88.1	96.3	-
CH ₃	5-CH ₃	70.8	51.4	68.3	87.2	-
CH ₃	6-CH ₃	74.5	59.8	67.8	99.0	-
Compound II		97.2	99.0	102.5	103.7	++
Compound III		72.5	54.2	53.1	61.3	++++

This test shows

a. that the prior art compound II, 3-hydroxy-4-methyl-norephedrine, does not penetrate into the brain and displace noradrenaline, which would result in a decrease of noradrenaline in the brain,

b. that the prior art compound III, α -methyl-m-tyramine, has an unwanted high sympathomimetic effect leading to excessive signs of piloerection, salivation, exoftalmos,

c. that the substances disclosed in this invention penetrate into the brain and cause release of noradrenaline through displacement (expressed as a decrease in noradrenaline) without causing disturbing sympathomimetic effects.

II. Toxicity

The intraperitoneal and the peroral toxicity was determined as LD₅₀ in mice.

Table 5

R ¹	R ²	LD ₅₀ in mice mg/kg i.p.	LD ₅₀ in mice mg/kg p.o.	Sympathomimetic effect observed
CH ₃	4-CH ₃	200	400	++
CH ₃	4-C ₂ H ₅	300	500	-
C ₃ H ₇	4-CH ₃	400	700	-
C ₂ H ₅	4-CH ₃	400	800	-
CH ₃	5-CH ₃	400	750	-
CH ₃	6-CH ₃	400	750	-
Compound III		100	200	++++
Compound II		150	300	++++

This test shows that the compounds disclosed in this invention have a low intraperitoneal and oral toxicity compared with the prior art compounds II and III.

12

III. Antihypertensive Effect

When 1-(m-hydroxy-p-methylphenyl)-propylamine-2 was given as a solution in the drinking water to normally hypertensive rats in doses of 5-10 mg/kg/day their blood pressure (170-200 mmHg) decreased to 100-120 mm Hg in a few days and remained there until the administration of the drug was stopped. The prior art compounds II and III did not react similarly when administered in the same dosage; compound II does not lower blood pressure and compound III causes an initial increase in blood pressure to 190-210 mm Hg due

10

30

35

40

45

to its sympathomimetic effect, whereafter the blood pressure decreases moderately.

This test shows that only compounds which penetrate into the brain and cause liberation and displacement of noradrenaline there have antihypertensive activity. The prior art compound III has an antihypertensive action which is masked by the sympathomimetic action of the substance leading to an initial undesirable increase in blood pressure.

IV. Effect as Releasers and Displacers of 5-Hydroxytryptamine in the Mouse Brain

Substances according to the invention were given intraperitoneally to mice (male, NMRI, b.w. 18-22 g, 6 animals/group). The amount of 5-hydroxytryptamine in the brain was determined fluorimetrically according to Bertler and Rosengren, Experientia 15 382 (1959), 4 hours after the administration.

The values are given in percents of normal values (460 ± 14 ng/g).

Table 6

R ¹	R ²	Dose mg/kg	Amount of 5-hydroxytryptamine after 4 hours; percent of normal values
CH ₃	4-CH ₃	50	82.2
CH ₃	4-C ₂ H ₅	50	62.2
C ₂ H ₅	4-CH ₃	100	51.0
CH ₃	5-CH ₃	100	89.1
CH ₃	6-CH ₃	100	87.3
C ₃ H ₇	4-CH ₃	100	85.4

Table 6-continued

R ¹	R ²	Dose mg/kg	Amount of 5-hydroxytryptamine after 4 hours; percent of normal values
Compound II		50	103.3
Compound III		50	119.1

This test shows that the compounds disclosed in this invention are able to liberate and displace 5-hydroxytryptamine in the mouse brain, in contrast to the related prior art compound III, α -methyl-m-tyramine. Higher doses than 50 mg/kg could not be used for the prior art compounds II and III due to the toxicity of these compounds.

We claim:

- 10 1. 1-(3-hydroxy-4-ethyl-phenyl)-propylamine(-2 or their optical antipodes) or therapeutically acceptable salts thereof.
- 15 2. 1-(3-hydroxy-4-methyl-phenyl)-butylamine(-2) or their optical antipodes or therapeutically acceptable salts thereof.
